UNITED STATES PATENT OFFICE.

HERBERT E. KEMPTON, OF CAMBRIDGE, MASSACHUSETTS, ASSIGNOR TO MARINE PRODUCER GAS POWER COMPANY, OF NEW YORK, N. Y., A CORPORATION OF NEW YORK.
FUEL-FEEDING MEANS FOR INTERNAL-COMBUSTION ENGINES.

1,092,109.

Specification of Letters Patent. Patented Mar. 31, 1914.

Application filed November 8, 1910. Serial No. 591,268.

To all whom it may concern:

Be it known that I, HERBERT E. KEMPTON, a citizen of the United States, and resident of Cambridge, in the county of Middlesex 5 and State of Massachusetts, have invented certain new and useful Improvements in Fuel-Feeding Means for Internal-Combustion Engines, of which the following is a specification.

10 In internal combustion engines wherein the hydrocarbon or other liquid fuel is injected into the cylinder or combustion space it is desirable that each charge of such fuel shall be quickly cut off at the proper moment, but where such liquid fuel has been injected while under relatively high pressure the objection has been found that although the stroke of the pump or the like, serving to force the liquid fuel to the nozzle. 15 or jet, has been stopped at the desired moment, yet by reason of the high pressure to which such fuel has been subjected the fuel has tended to continue to flow as well as to exude or drip from the nozzle after the forcing action of the pump has ceased, thereby over-supplying the fuel.

The object of my invention is to cause the sudden cutting off or stoppage of the flow of the fuel from the nozzle or jet at the desired 20 moment, and to prevent the exudation or dripping of fuel from the nozzle as soon as the required amount of fuel has been ejected therefrom.

In carrying out my invention I provide a 25 nozzle or jet communicating with the cylinder or combustion space of an internal combustion engine, a pump or the like communicating by a suitable passage with such nozzle, one or more check valves in such 30 passage, and means to maintain communication between the fuel forcing member of the pump and the nozzle or jet, as through or past one of such valves, whereby on one 35 stroke of the pump member the fuel will be forced from the nozzle, as in the form of a spray or fog, and upon the start of the return stroke of such pump member the high pressure of the fuel in said passage will be relieved, thereby quickly cutting off flow of 40 fuel from the nozzle and preventing or limiting the flow of fuel from such nozzle until the next power stroke of the pump, and so on.

My invention also comprises novel details of improvement and combinations of parts 55 that will be more fully hereinafter set forth and then pointed out in the claims.

Reference is to be had to the accompanying drawings forming part hereof, wherein,

Figure 1 is a vertical section of a portion 60 of an internal combustion engine embodying my invention; Fig. 2 is an enlarged central section through the fuel pumping device and nozzle or jet, illustrating my improvements; Fig. 3 is a central section at right 65 angles to Fig. 1; Fig. 4 is an enlarged detail sectional view of the nozzle or jet, Fig. 5 is a section on the line 5, 5, in Fig. 2, looking in the direction of the arrows. Fig. 6 is a section on the line 6, 6, in Fig. 3, and 70 Fig. 7 is a section on the line 7, 7, in Fig. 3.

Similar numerals of reference indicate corresponding parts in the several views.

It will be understood that my invention is 75 applicable for use in any suitable internal combustion engine, wherein liquid fuel is adapted to be utilized when compressed with air. I have illustrated my invention applied to a cylinder or combustion chamber containing air under compression into which fuel is injected.

I have shown my improvements as applied to a two-cycle internal combustion engine, wherein the numeral 1 indicates a cylinder, 2 a combustion space, 3 the main shaft, 4, the exhaust passage, and 5 the air intake port. In the example illustrated I have shown the type of engine having differential pistons 6, wherein the piston enlargement 6^a, working in a space 7, draws air into manifold 8 and space 7 through the valves 9 on the outstroke, and on the instroke compresses such air and drives it through the valves 10 into the upper chamber 90 of the manifold and thence through the intake port 5 of a cylinder. Thus, as shown in Figs. 6 and 7, as the several cylinders communicate through the ports 1^x with the upper chamber 8^a of the manifold above 100 valves 10, and the spaces 7, communicate with the ports along with the lower chamber 8^b of the manifold, it will be understood that the enlargements 6^a of the pistons alternately maintain air compressed in chamber 8^a ready 105 to be admitted through a port 1^x into a cyl-

inder when its piston uncovers the corresponding port 1^x, so that each cylinder takes air from the manifold as required.

Figs. 1, 3, 6 and 7 illustrate a portion of a multicylinder engine, the air ports of which cylinders communicate with manifold 8 in a well known manner. At 12 is a suitable fuel supply pump, shown provided with a plunger or piston 14 operated by a cam 15 on shaft 3, plunger 14 being shown provided with a roller 16 coacting with said cam, said plunger being normally pressed outwardly by spring 17 to act against said cam. The engine I have illustrated is shown provided with a suitable governor 18 acting through collar 19, on shaft 3, and lever 20 to regulate the operating thrust of plunger 14 in a well known manner.

Two pumps and corresponding levers 20, etc., are shown for use on the multicylinder engine. When cam 15 rotates with shaft 3 it operates plungers 14 to force oil to the cylinders. As the speed increases the governor balls 18 move outwardly, drawing collar 19 toward the left in Fig. 1, and causing levers 20 to move outwardly and correspondingly move the plungers away from the cam to shorten the effective stroke of the pumps by providing lost motion between the cam and plungers. As the load increases, causing the engine to slow down, and the governor balls 18 approach, levers 20 correspondingly approach shaft 3 to provide an increased plunger stroke, and so on.

Plunger 14 draws liquid fuel through a suitable spring-pressed valve 21 into chamber 22, from a supply pipe 23, in any well known manner. Pump chamber 22 communicates by a suitable passage with a nozzle or jet 24 that communicates with the cylinder or combustion space of the engine. I have shown a pipe 25 forming part of the passage between chamber 22 and nozzle 24.

At 26 is a check valve, shown fitted to slide in a bore 27^a in a plug 27, the latter being shown provided with threads screwed into an opening in pump casing 12, said plug having an opening 27^b communicating with chamber 22 and with bore 27^a, valve 26 fitting at its lower end against a seat 27^c in plug 27. Valve 26 may be substantially of rectangular form, as shown in Fig. 5, whereby fuel may flow past the valve through bore 27^a when the valve is unseated. Valve 26 is shown provided with a bore 26^a and with a relatively small orifice 26^b communicating with chamber 22 through opening 27^b. A cap or nut 28 is shown screwed upon plug 27 and contains a spring 29 normally tending to force valve 26 upon its seat. Pipe 25 is shown fitted closely to cap 28 by the nut 30, screwed on an extension of said cap, and packing 31, whereby packing 31 in a socket at the end of plug 28 may serve to make tight joints to resist high pressure. Nozzle

or jet 24 is shown carried by a tubular plug 32 shown provided with threads screwing into a hole 2^a in the engine wall, whereby the nozzle 24 communicates with the combustion space. Pipe 25 is fitted oil-tight to the outer end of plug 32, for which purpose I have shown a cap 33 screwed upon the end of plug 32 and receiving the end of pipe 25, packing 34 being compressed in the socket at the end of plug 32 to make an oil-tight fitting for pipe 25 at the plug. Plug 32 has a bore 32^a and seat 32^b to which a check valve 35 is fitted. Nozzle 24 is shown provided with a tapering bore 24^a receiving a tapering spirally threaded piece 36, the channel between the threads of piece 36 communicating with bore 32^a, which provides a spiral passage for the outflow of the fuel whereby comminution of the same is aided. A spring 37 bears against threaded piece 36 and against valve 35, being shown extending into a bore 35^a in said valve, normally tending to hold said valve upon its seat 32^b and also maintaining piece 36 in bore 24^a. Valve 35 may be made in cross section similar to valve 26 to permit the flow of fluid past said valve from bore 32^a, although said valves may be arranged in any well known manner to permit the flow of fluid past the same. Ignition may be produced by a hot ball A or in other well known manner.

With the parts arranged as set forth, i. e., the nozzle attached to the engine and connected with the pump by pipe 25, the operation may be described as follows: Assuming that the pump and the passages and nozzle 24 are charged with liquid fuel, a pressure stroke of the pump plunger will compress such fuel and force a portion thereof through the nozzle under pressure by reason of the small area of the nozzle orifice 24^b relatively to the displacement of the plunger, the fuel so injected into the engine cylinder or combustion space being in comminuted form, such as a spray or fog, the valves 26 and 35 unseating on such stroke. Owing to the relatively high pressure to which the liquid fuel is thus raised the same would continue to flow for a short period from the nozzle orifice, except that as soon as the pump plunger starts to move on the return or suction stroke the pressure of the fuel in pipe 25 and the communicating passages is relieved through the opening or orifice 26^b of valve 26, enabling a small portion of such fuel to flow from plug 27 into chamber 22, valve 35 will then seat, and excess fuel is cut off or prevented from flowing from nozzle orifice 24^b, but opening 26^b is sufficiently small so as not to unduly permit withdrawal of fuel from pipe 25 and the connecting passages. Upon the next pressure stroke of plunger 14 the fuel will be again forced through the nozzle, and again

instantly cut off by the relief of pressure thereon through opening 26^b, and so on, valve 26 serving in the usual way of a check valve to resist the back suction through pipe 25, etc., of the fuel, except for the small amount that may be drawn back through opening 26^b to relieve pressure in such pipe. By means of my improvements, while the comminuted fuel may be delivered from the nozzle orifices as rapidly as required, the danger of an overflow of fuel into the engine cylinder, such as fuel oil, is prevented, which would otherwise have a tendency to impair lubrication and cause carbonization, etc., within the cylinder, and a saving of fuel is effected, and the efficiency of the engine is increased.

I have shown two pumps 12 in Fig. 1 adapted to be operated in the manner set forth for supplying a two-cylinder engine, but it will be understood that my improvements are equally applicable in a single cylinder engine or one having any desired number of cylinders arranged with a required number of nozzles, pumps and the like.

While I have illustrated my improvements as applied to a well known type of two-cycle two-port engine, it will be understood that my invention is applicable to other forms of engine, and also that my invention is not limited to the details and arrangements set forth as the same may be varied, within the scope of the appended claims, without departing from the spirit of the invention.

Having now described my invention what I claim is:—

1. The combination of a nozzle, fluid forcing means, a passageway between the nozzle

and fluid forcing means, said passageway having an orifice maintaining constant communication between the nozzle and the fluid forcing means, and a check valve between the nozzle and the fluid forcing means.

45

2. The combination of a nozzle, a pump, a passage connecting the pump with the nozzle and having an orifice maintaining constant communication therebetween, and a check valve in said passage to be seated upon the intake stroke of the pump.

3. The combination of a nozzle, a pump, a passage connecting the nozzle with the pump chamber, and a check valve in said chamber provided with an opening maintaining constant communication between said passage and said chamber.

55

4. The combination of a nozzle, a plug connected with the nozzle and provided with a bore, a check valve in said bore, a pump, a passage connecting the pump chamber with the bore in said plug, the pump having a check valve provided with means to maintain the pump in constant communication with said passage.

65

5. The combination of a nozzle, a plug connected with the nozzle and provided with a bore, a check valve in said bore, a pump, a passage connecting the pump chamber with the bore in said plug, the pump having an apertured valve maintaining constant communication between the passage and the pump.

70

Signed at New York city, in the county of New York, and State of New York, this 5th day of November, A. D. 1910.
